AUTOMOBILE EMBLEM PLATE OR SIMILAR ARTICLE

Herbert Wimberly, Baton Rouge, La.

Application May 25, 1949, Serial No. 2,880

Term of patent 14 years

(Cl. D14—6)

To all whom it may concern:

Be it known that I, Herbert Wimberly, a citizen of the United States, residing at Baton Rouge, in East Baton Rouge Parish, and State of Louisiana, have invented a new, original, and ornamental Design for an Automobile Emblem Plate or Similar Article, of which the following is a specification, reference being had to the accompanying drawing, forming part thereof.

Fig. 1 is a front view of the emblem, showing my design;

Fig. 2 is a view in edge elevation of the emblem shown in Fig. 1.

The dominant features of my design reside in the portions shown in full lines.

I claim:

The ornamental design for an automobile emblem plate or similar article, substantially as shown and described.

HERBERT WIMBERLY.
